MINNEAPOLIS, MINNESOTA

DISK WHEEL

Application filed March 30, 1921. Serial No. 456,843.

This invention is a disk wheel for use on vehicles and while particularly directed to disk wheels embodying two or more disks is equally applicable to disk wheel construction embodying a single disk.

A common form of disk wheel now on the market embodies two disks, which are spaced apart at their centers by spacing means positioned between the disks, so as to lend lateral strength to the wheel and at the same time provide proper bearing between the disks and the hub of the wheel.

A further reason for spacing the centers of the disks apart in some disk wheels is to permit of their substitution for wooden wheel spokes upon the hub of a conventional wooden wheel, this being desirable wherever possible to obviate the necessity of constructing special hubs for the disk wheels. The reason for spacing the centers of the disks apart in wheels used on conventional wooden hubs is to permit of the employment of the hub bolts used to maintain the wooden spokes in place. When the centers of the disks are spaced apart as described, the same distance as the thickness of the wooden spokes at the hub, the wooden spokes may be removed and the disk wheel readily substituted on the hub therefor and secured in place by the hub bolts.

When the disks of a wheel are spaced apart at their centers for any of the reasons specified, means must be provided for accomplishing the spacing of these parts of the disks. This means is invariably in the form of a separate and independent member or members positioned between the disks and intended to rigidly space them apart. When such means is positioned between two disks, it is difficult to firmly screw such means in position, so as to avoid rattling and other detrimental features and in the event of breakage of such spacing means, it is practically impossible in a majority of structures to properly repair the same.

With the foregoing considerations in mind, the object of the present invention is to provide means whereby the spacing apart of the disks of a two disk wheel at their centers is not present in this structure, but,

in contra-distinction, when two disks are employed they are brought into face abutting relation at their centers and separate and independent means is positioned exteriorly of the disks for imparting to the wheel the desired thickness or dimensions at its center.

The present invention is so comprehensive in its application, that it may be carried out in wheels embodying but a single disk provided at its center with filler means so associated with the disk as to impart the desired central dimension thereto whereby a single disk wheel may be readily associated with the conventional wooden wheel hub as readily as a double disk wheel embodying the present invention.

A marked advantage of a wheel embodying this invention is that it is strong and durable in construction, may be economically and efficiently manufactured and is durable in use.

Features of the invention, other than those specified, will be apparent from the herein-after detailed description and claims, when read in conjunction with the accompanying drawings.

The accompanying drawings illustrate different practical embodiments of the present invention, but the constructions therein shown are to be understood as illustrative, only, and not as defining the limits of the invention.

Figure 1 is a fragmental section perspective of a two disk wheel embodying the present invention.

Figure 2 is a diametric section of a complete wheel embodying the structural features set forth in Figure 1.

Figure 3 is a radial section showing two disks in assembled relation and forming the basis of a wheel of the kind shown in Figure 2.

Figure 4 is a radial section of a wheel section embodying a single disk, constructed in accordance with the present invention and having associated therewith means for imparting to the center of the wheel the desired thickness.

Figures 5, 6 and 7 show slightly modified forms of construction for a wheel embody-

ing two disks. These figures are fragmental radial sections.

Figure 8 is a perspective view of a filler member employed in the construction of Figures 1, 2 and 6.

5 Figure 9 is a perspective view of one of several bushings which may be employed in conjunction with a wheel embodying the present invention to facilitate its positioning upon hubs of different sizes.

10 Figure 10 is a diagrammatic section through a wheel showing the manner of employing a bushing of the character illustrated in Figure 9.

15 Figure 11 is a fragmental view of a peripheral portion of a disk wheel showing the manner in which one or both of the disks may be formed to render the tire nipple more accessible than theretofore;

20 Figure 12 is a section on the line 12—12 of Figure 11; and

Figure 13 is a vertical section illustrating a modified form of the invention.

25 In practice, the wheel of the present invention may partake of a large number of different forms. The invention may be embodied in a wheel having a single disk and is equally applicable to wheels formed with two disks. The manner of securing the disks 30 to one another at the outer margin or margins, as well as the manner of mounting the rim on the disk or disks, forms no part of the present invention, and in its commercial forms, the wheel may embody disks of different radial section.

35 The invention relates directly to the hub portion of a steel wheel embodying either one or more disks and in the accompanying drawings, I have shown a purely illustrative structure, which is to be understood as in no-wise defining the limits of this invention, which is directed to obtaining proper thickness or dimensions of a disk wheel at its center or hub portion.

40 In the accompanying drawings, several ways of obtaining this result are shown, all of which ways entirely overcome the disadvantages inherent in structures wherein two disks are spaced apart at their centers 45 or wherein one disk is given the desired thickness at its center by providing spacing blocks at both sides of the disk.

50 Referring to the illustrative showing in the drawings, and more particularly to the 55 construction as illustrated in Figures 1, 2 and 3, 15 designates any suitable and conventional form of rim which is spaced from a hub 16 by two disks 17 and 18. These disks 60 may be of substantially the same diameter, i. e., both extend the entire distance from the hub to the rim, or the hub may be spaced from the rim by a single disk which extends the entire distance from the hub to the rim 65 and has associated therewith a reinforcing disk after the same general plan as shown in

my copending application, Serial No. 319,091, filed August 22nd, 1919, on "pressed steel wheel". However, for the purpose of illustration, two disks of the same size are shown.

70 The hub 16 may be of any conventional form, such for example as is in common use in connection with wooden wheels of the conventional kind. Such a hub is provided with a fixed flange 20 and a removable flange 19, which flanges are bolted together by hub bolts 21 and in ordinary practice serve to clamp the spokes of a wooden wheel between the fixed and removable flanges 20 and 19.

75 In carrying out the present invention in a wheel embodying two disks, which, in practice, are preferably dished substantially complementary to one another, the outer disk 17 is constructed in the usual way, but the inner disk 18 is formed at its center so that an appreciable part of the portion of such disk 80 which is marginal of the central hub opening thereof will lie in face abutting contact with the adjacent or opposed face of the disc 17, as shown at 22. In other words, the 85 central portions of the disks or those portions thereof immediately surrounding the hub opening are in face abutting relation to one another and are not spaced apart as heretofore.

90 In order that a wheel so constructed may have proper thickness or dimensions adjacent the hub, I preferably associate with the construction already described a member 23 which may be graphically termed a filler as it 95 serves to cooperate with the discs in filling out the space between the fixed and removable flanges 20 and 19 of the hub. This filler may be conveniently formed after the manner shown in Figure 8, wherein it is illustrated as embodying a tubular section 24 provided 100 at one end with a radially extending flange 25. In assembling the parts of the wheel, the filler 23 is brought into the position shown in Figure 1 and is secured in this position in any suitable and convenient manner. For 105 example, the filler may be firmly welded in place as shown at 26 and 27. To facilitate the welding operation of the outer margin of the flange 25 of the filler to the plate 18, and also to render the inner surface of the wheel smooth and free from projections, the plate 18 may be offset at 27 so as to provide a 110 depression in the tapered face of the inner plate 18 under which the flange 25 of the filler loosely seats. A fillet of metal as shown at 26 may be conveniently deposited between the outer margin of the flange 25 and the offset 27, by any well known welding process, 115 thereby producing a smooth and uninterrupted inner surface on the wheel and firmly 120 uniting the flange of the filler and the disk 18.

125 The free end of the sleeve portion 24 of the filler is united to the inner margins of the plates 17 and 18 by the welded fillet 27 to produce a strong and permanent union between 130

these parts. In the construction of Figures 1, 2 and 3, the inner margin of the disk 18 is turned inwardly as at 28 and seats on the outer circumference of the sleeve-like portion 24 of the filler. This construction is preferable as it produces a strong and entirely satisfactory union when welded as described, although, if desired, this construction may be varied as shown in Figure 5, wherein the inner margin of the disk 18 is formed the same as the inner margin of the disk 17 and the free end of the sleeve 24 of the filler is flared out at 29. In such a construction, the parts are welded together as shown in Figure 5. The two described ways of securing the sleeve portion of the filler to the inner margins of the disks 17 and 18 have been found to give satisfactory results in practice, but it will be understood that they may be united in other ways than as shown and through other means other than welding without departing from this invention.

A wheel constructed as described is adapted to be slipped over the hub of a conventional wooden wheel, or for that matter any other suitable form of hub, and secured in place by the hub bolts which are adapted to pass through alined holes formed in the disks and in the flange of the filler. Figures 1 clearly shows holes 30 provided for this purpose, formed in the face abutting portions of the disks 17 and 18 and alined holes 31 formed in the flange 25 of the filler.

It may be here noted that when a wheel so constructed is mounted on a hub and the hub bolts tightened, the sleeve-like portion 24 of the filler will take the greater portion of the tension imposed upon the construction by the hub bolts, and the filler will be therefore reinforced against bending of its flange 25 with respect to its sleeve portion 24 by the portion 32 of the disk which extends transversely of the wheel and from the base of the depression in which the flange of the filler seats to the portion 22 of the disk 18, which is in face abutting relation to the center of the disk 17.

The construction is strong and rigid and no strain that can be placed thereon by the bolts 21 will be sufficient to disrupt the parts.

However, if desired, the structure may be further reinforced by positioning a core 33 of wood or any other suitable material within the space left between the center of the disk 18 and the flange 25 of the filler after the manner shown in Figure 6. This core may entirely fill such space as shown.

I am aware, moreover, that instead of using a metallic filler such as shown in Figure 8, the filler may be made entirely of wood, fibre or other suitable substance to the exclusion of metallic parts and may be made solid and associated with the disk 18 after the manner shown in Figure 7, wherein the filler is described by the reference character 23^a. If desired, the holes in the filler 23^a through

which the hub bolts pass may be lined with a suitable bushing 34, metallic or otherwise, but this is not necessarily essential. Furthermore, in the device of Figure 7, the parts are not shown as secured together though the disks may be welded, riveted or otherwise attached to one another and the filler 23^a may be held in position in any desired way.

In order that disk wheels of different sizes may be associated with a hub, which may not necessarily be of the same size, I may use in conjunction with the wheel of this invention, a bushing 35 shown in Figure 9, which bushing may be of wood, fibre, felt or any other suitable material so as to absorb shocks to which the wheel may be subjected. However, this bushing may be of metal if desired. The manner of associating the bushing with the wheel and hub is shown in Figure 10 and it will be understood that in practice bushings of different sizes may be employed so as to enable the wheel to fit over a hub of smaller dimensions than that for which the wheel was built.

In the foregoing discussion of the invention, the same has been dealt with in conjunction with wheels embodying two disks, but it is to be understood that it is equally applicable to wheels embodying a single disk. In Figure 4, a filler of the character shown in Figure 8 is associated with a single disk 36 and its flange is shown as riveted at 37 to the disk, while its sleeve portion is illustrated as welded at 38 to the inner margin of the disk. Any of the other forms of the filler member than the metallic form shown in Figure 4 may be employed with a single disk without departing from this invention.

One of the most marked inconveniences inherent in the employment of disk wheels as now made is the inaccessibility of the tire nipple which is so positioned that in many instances, the nipple is very difficult to get at and accordingly it is the usual practice to inflate a tire on a demountable rim before positioning the tire on the wheel.

In Figures 11 and 12 of the drawings, disk wheel construction is illustrated wherein the parts are so formed that the nipple is in a convenient and accessible position from the outside of the wheel. This end is accomplished by stamping out a recess from the inside of the outside disk 17^a, so as to provide a flat abutment portion 39. This portion is provided with a nipple hole 40 in alignment with a nipple hole 41 in the rim 15^a and the tire nipple is adapted to project through the alined holes 41 and 40 and into a convenient accessible position. The cap 42 of the nipple 43 may be easily screwed on and removed from the nipple and the outer end of the latter partakes of a position wherein it is readily accessible from the outside of the wheel. This is an important feature in disk wheel

construction and overcomes the long felt disadvantage in disk wheels.

In the formation of the disk as shown in Figures 11 and 12 no pockets are left on the outer face of the disk for the accumulation of dirt and mud, and the wheel may be washed as readily as though the shoulder portion 39 were not formed therein.

The construction of Figures 11 and 12 may 10 be carried out in double disk wheels, as well as in single disk wheels, and is accordingly not restricted to the specific showing of Figures 11 and 12. Thus in Figure 13 I have shown this feature incorporated in a double 15 disk wheel comprising two disks 17^b and 18^b. The disk 17^b is constructed in the same manner as the disk 17^b of Figure 12 and the disk 18^b is merely added to this construction. The tire nipple is shown at 34 and the opening 20 for such nipple is illustrated at 40.

It will be apparent from the foregoing description that the wheel of the present invention embodies several features of novelty, which when combined in a wheel result in a 25 structure of pronounced utility, economy and efficiency. It will be understood, however, that some of the features enumerated may be employed in wheel construction without necessarily employing all. Accordingly, the 30 present invention is to be construed as broadly novel as is commensurate with the appended claims.

Having thus fully described the invention, what I claim as new and desire to 35 secure by Letters Patent is:

1. A disk wheel embodying a hub provided with fixed and removable flanges, a plurality of disk portions, each of which is provided with a hub opening, and spacing means positioned wholly between the disk portions and one of the flanges of the hub to permit the clamping of the disk portions between the flanges of the hub.

2. In a disk wheel, a hub provided with a 45 fixed flange and a removable flange, a pair of sheet metal disks apertured to receive said hub and being in face abutting relationship adjacent thereto, an annular filler member receivable upon said hub alongside one disk and means extending through said disks, filler and flanges to hold said parts together.

3. In a disk wheel, a hub having a fixed flange, a plurality of sheet metal disks apertured to receive said hub and being in face 55 abutting relationship adjacent thereto and in abutting relationship to the fixed flange thereon, an annular filler receivable upon said hub alongside said disks and secured to one of them along its outer margin spaced from the 60 hub, a removable flange receivable upon said hub adjacent to said filler, and means engaging said removable flange to hold said parts together.

4. In a disk wheel, a rim, an apertured sup- 65 porting sheet metal disk, said disk having a

shoulder encircling the aperture, a hub receivable therethrough and provided with a flange adapted to abut one face thereof, an annular angular sheet metal filler having a cylindrical portion receivable upon said hub and adapted to engage the disk adjacent to the hub, said filler member having a radial portion the margin of which engages the shoulder of the disk, a removable flange mounted upon the hub alongside the filler member and means securing said removable flange in place.

5. In a disk wheel, a hub provided with a fixed radial flange, a pair of sheet metal disks apertured to be received upon the hub abutting said flange, a filler member receivable upon the hub having a cylindrical portion embracing the hub and extending underneath one disk and engaging the other disk, said filler member having a radial portion extending outwardly from the hub and engaging the adjacent disk and means securing said parts together.

In testimony whereof, I have signed my name to this specification.

DAVID H. BELLAMORE.
